[57] CLAIM

The ornamental design for a mounting clip, as shown and described.

DESCRIPTION

FIG. 1 is a front view of a mounting clip showing my new design.

FIG. 2 is a side view thereof.

FIG. 3 is a bottom view thereof.

FIG. 4 is a front view of a second embodiment showing my new design.

FIG. 5 is a side view thereof.

FIG. 6 is a bottom view thereof.

FIG. 7 is a front view of a third embodiment showing my new design.

FIG. 8 is a side view thereof.

FIG. 9 is a bottom view thereof.

FIG.1.

FIG.2.

FIG.3.

FIG.4.

FIG.5.

FIG.6.

FIG.7.

FIG.8.

FIG.9.
